UNITED STATES PATENT OFFICE.

MILTON P. ALTSCHUL, OF CLEVELAND, OHIO, ASSIGNOR TO THE STANDARD ENVELOPE MANUFACTURING COMPANY, OF CLEVELAND, OHIO, A CORPORATION OF OHIO.

ENVELOPE.

Application filed May 13, 1922. Serial No. 560,609.

To all whom it may concern:

Be it known that I, MILTON P. ALTSCHUL, a citizen of the United States, residing at Cleveland, in the county of Cuyahoga and 5 State of Ohio, have invented a certain new and useful Improvement in Envelopes, of which the following is a full, clear, and exact description, reference being had to the accompanying drawings.

10 This invention relates to mailing envelopes and has for its object to provide an improved envelope which may be mailed under one address and then re-mailed to the sender or other party under another address. For this purpose the envelope is provided on the back thereof with the address of the party to whom it is to be sent to first, and the front or face of the envelope is provided with the address of the sender or 15 other party to whom it is to be remailed. This envelope is then enclosed in a window envelope with the address on the back showing therethrough.

For a more detailed description of the invention reference may be had to the accompanying drawing wherein Fig 1 is a front elevation of the envelope enclosed in a window envelope and ready for mailing; Fig. 2 is a front elevation of the envelope 20 removed from the window envelope; and Fig. 3 is a rear elevation thereof.

In practicing my invention I provide an envelope which has the rear face 2 thereof provided with the name and address of the 25 party to whom the letter is to be initially sent. This name and address which is indicated at 3 is so positioned thereon that it will occupy an area which coincides with the transparent portion 4 of the window 30 envelope 5 and in order to easily locate such area I may place a guide line 6 thereon enclosing the same. At a point removed from such area I print the word "From" so that it will be invisible when the envelope 1 is 45 enclosed in the window envelope.

The front face 7 of envelope 1 is provided with the name and address of the sender or other party to whom the envelope is to be returned. This name and address which is indicated at 8 may be located on the face of the envelope in the usual place for such information. The left hand portion 9 of the face 7 is reserved for printing which may convey a message, advertisement or other information. In the present instance I have

shown as an example, certain wording thereon for use between two business houses.

In operation the letter originates at the company of John Doe, who for convenience may have the face 7 of the envelope printed 60 as shown in large quantities, and the rear of the envelope printed with the guide line 6 and the word "From". These envelopes then have the name and address of the parties to whom they are to be 65 sent placed in the area enclosed by guide line 6. Each envelope is then placed in a window envelope 5 with the last mentioned name and address showing through the window 4 and the letter is then mailed. The 70 A. B. Smith Company receiving this letter finds directions in the left hand portion 9 of envelope 1 and merely affixes the proper stamp and mails the envelope. The address 3 which served as the first mailing address 75 then becomes the return address. The A. B. Smith Company may enclose samples for The John Doe Company in envelope 1, in which case The John Doe Company can supply the necessary information as to how 80 their products can be used profitably by The A. B. Smith Company. If no samples are enclosed and the envelope is returned empty, The John Doe Company sends a representative to call and explain how they 85 can cooperate with The A. B. Smith Company.

It will thus be apparent that the Smith Company is not required to write a letter or address an envelope as such is furnished by 90 The John Doe Company.

While I have shown my invention applied to ordinary envelopes for letters, it will be obvious that it may be applied to other types of envelopes, cartons, etc., and the 95 term envelope used in the appended claims is intended to cover such other enclosures.

Having thus described my invention, what I claim is:

1. The combination of two envelopes, one 100 placed within the other, the inner envelope having a different address on each face thereof, and the outer envelope having a transparent window therein, the address on one face of said inner envelope being 105 adapted to register with said transparent window.

2. As a new article of manufacture, an envelope having the address of one party on the front face thereof and the address of a 110

second party on the rear face thereof, said last mentioned address being so located on the back of the envelope as to coincide with the transparent portion of a window envelope when placed therein.

3. The combination of two envelopes, one placed within the other, the inner envelope having the address of one party on the front face thereof and the address of a
10 second party on the rear face, and the outer envelope having a transparent window therein, the address of said second party on the rear face of said inner envelope being adapted to register with said transparent
15 window.

4. The combination with two envelopes, one placed within the other, the inner envelope having the address of the sender on the front face thereof and having printed matter thereon in a space removed from said address, the rear face of said envelope having the address of the party to whom it is to be sent, and the outer envelope having a transparent window, the address on the rear face of said inner envelope being adapted to register with said transparent window. 20 25

In testimony whereof, I hereunto affix my signature.

MILTON P. ALTSCHUL.
